G. FORNACA

SPRING CONTROLLED VALVE

Filed Sept. 2, 1925

UNITED STATES PATENT OFFICE.

GUIDO FORNACA, OF TURIN, ITALY.

SPRING-CONTROLLED VALVE.

Application filed September 2, 1925, Serial No. 54,041, and in Italy September 8, 1924.

The object of this invention is to provide an improved arrangement of spring-controlled valve which is primarily intended for internal combustion engines but may 5 also be used with other apparatus. By a spring controlled valve I mean a valve equipped with spring means wherein energy is stored for returning the valve when this is moved in one direction.

10 Generally the valves of internal combustion engines are maintained on their seatings by helical springs one for each valve arranged coaxial with the valve stem. With this arrangement the fracture of the 15 single spring renders the valve inoperative and necessitates immediate replacement.

According to the present invention this inconvenience is eliminated by substituting for the single spring a plurality of springs 20 grouped around the valve stem and maintained in position by a disc secured to said stem.

By this arrangement the reaction is distributed uniformly over a group of springs, 25 and it is much more difficult for fractures to occur. Moreover, if one of the springs does break the valve can continue to operate without disadvantage, and the broken spring can be replaced at any convenient time and 30 place. The arrangement also ensures a better cooling of the springs, their normal working temperature being obviously lower than that of the ordinary arrangement in which there is a single spring coaxial with the 35 valve stem.

A feature of the invention consists in the manner of mounting the group of springs so that, while they are perfectly guided, they can be easily and quickly removed and re- 40 placed.

An embodiment of the invention suitable for internal combustion engines is illustrated, by way of example, on the accompanying drawing.

45 Fig. 1 is a vertical section, and Fig. 2 a cross section (in the plane C—D of Fig. 1).

In the drawing, the reference numeral 1 indicates the stem of a mushroom or poppet valve 2, furnished with a large disc 3. An 50 annular cup 9 rests on a fixed shoulder 6 of the engine, and in the bore of the cup is in-

serted a guide 7 for the stem 1 of the valve 2. This guide is provided with a flange 8 which engages the cup and is itself engaged by a similar flange on a guide box 15 for the 55 group of springs 4. The lower part of the guide box fits into the cup 9 and has a flange 15' serving as a support for the springs 4 which pass through openings (see Fig. 2) in the upper part 14 of the box 60 and bear against the disc 3 secured to the valve stem.

The disc 3 has a conical bore which is engaged by a divided cone 13 on the valve stem to prevent the disc from moving upward 65 on the valve stem. To prevent said disc from being displaced downward with respect to the valve stem, a cap 11, and a suitable ring 12 are provided. By this arrangement the disc 3 may be easily removed 70 and replaced.

What I claim is:

1. In a spring controlled valve, a member having a valve seat therein, a sleeve mounted in said member, a stem on the valve 75 movable in the sleeve, a cup mounted on the sleeve engaged by a flange on the latter, a guide box mounted on the sleeve engaging said flange, a series of springs grouped around the valve stem and located in pockets 80 in the guide box, and a disc on the valve stem forming an abutment for the springs whereby the latter are maintained under tension to normally seat the valve.

2. In a spring controlled valve, a member having a valve seat therein, a sleeve mounted in said member, a stem on the valve movable in the sleeve, a cup mounted on the sleeve in engagement with a flange on the latter, a guide box mounted on the sleeve engaging said flange, a series of springs grouped around the valve stem and located in pockets in the guide box, a disc on the valve stem having a conical bore, a divided 90 conical cap secured to the stem and seated in said bore, said disc forming an abutment for the springs whereby the latter are maintained under tension to normally seat the valve.

In testimony that I claim the foregoing 100 as my invention, I have signed my name.
GUIDO FORNACA.
